UNITED STATES PATENT OFFICE

AIME BARTHELEMY FOURNIER, OF PARIS, FRANCE, ASSIGNOR TO UNION D'ÉLECTRICITE, OF PARIS, FRANCE, A CORPORATION OF FRANCE

INSTANTANEOUS SELECTIVE PROTECTIVE ARRANGEMENT FOR DIRECT CURRENT NETWORKS

Application filed September 10, 1931, Serial No. 562,184, and in France September 26, 1930.

The present invention has as object an instantaneous selective protective arrangement for direct current networks, against short circuits which may arise either directly between the conductors or between these conductors and earth.

The invention consists in utilizing the short period which succeeds the establishment of a short circuit and in causing a release relay to function by means of an electromotive force proportional to the sum of the variations (as a function of time) of the currents which enter or leave each one of the extremities of the section of the protected circuit. When this relay is excited, it produces the simultaneous opening of all the circuit breakers placed at the various extremities of the protected section.

The principle of the invention will be better understood from the following description in relation to the annexed drawing.

In the drawing, 1 represents a continuous current conductor from which are derived a certain number of branches 2, 3 and 4. At each end of the conductor 1, serving for its protection against short circuits and at the beginning of each of the branches 2, 3 and 4, circuit breakers 5, 6, 7, 8 and 9 are placed. These circuit breakers, furnished with trip coil may be of any type usually employed in practice. At each of the extremities of the conductor 1, and in each branch, there are also installed current transformers 10, 11, 12, 13, 14 the primary circuits of which are each connected in series with the corresponding continuous current conductor. The secondary windings of these current transformers are all connected in parallel and feed the winding 15 of a single relay 16. When the winding 15 is excited, the movable contact 17 of the relay 16 comes in contact with the fixed contact 18 of this relay which causes, by way of the connections 19, the simultaneous excitation of release bobbins of interrupters 5, 6, 7, 8 and 9 and as a result the opening of the latter.

The current transformers 10, 11, 12, 13 and 14 may be of any type but they must have identical characteristics. According to a preferred mode of carrying out the invention,

the cores of these current transformers include a gap or are constituted of non-magnetic material which permits of avoiding the disturbances which would be caused by the more or less great saturation of the various cores and, as a result, of assuring a similar working of all the transformers.

The mode of working of the arrangement is then as follows:

In the absence of any short circuit, the currents which flow in the primaries of the current transformers being continuous currents, the electromotive force induced in the secondary of these transformers, proportional to the variation of the flux induced by the primary as a function of time, is nothing and the relay is not excited.

When a short circuit is produced in the continuous current network, but outside the protected zone limited by the circuit breakers 5, 6, 7, 8 and 9, at a, for example, the continuous current varies more or less sharply and this variation induces electromotive forces in the secondaries of the current transformers. But as by hypothesis the short circuit has taken place outside the zone limited by these current transformers, the sum of the currents which enter and which leave this section, for example in the sense of the arrows, is nothing and as a result the sum of the derivatives with respect to time of these currents is also nothing. It results that the sum of electromotive force induced at the terminals of the secondary of the current transformers is nothing and that the relay 16 is not excited.

If, on the other hand, a short circuit is produced in the conductor 1 within the protected zone, the sum of the currents entering and leaving this zone is not nothing, nor is the sum of the derivatives with respect to time of these currents. The transitory period during which the short circuit is established thus induces at the terminals of the secondaries of the current transformers electromotive forces of which the sum is not nothing and which cause the excitation of the relay 16 and as a result the simultaneous opening of the circuit breakers guarding the section.

What I claim is:—

1. Protecting system for a zone of direct current electric conductors comprising circuit breakers on each conductor inside said zone, for each circuit breaker a trip coil, an electric power supply able to feed said coils, a relay controlling said feeding current, and means for energizing said relay by a current proportional to the variations of the algebraic sum of the currents entering the zone to be protected.
  2. Protecting system for a zone of direct current electric conductors, comprising circuit breakers on each conductor inside said zone, for each circuit breaker a trip coil, an electric power supply able to feed said coils, a relay controlling said feeding current, current transformers all having the same characteristics, the primary winding of each of which is inserted in one conductor at the point where the same crosses the zone border and means to connect in parallel with the relay coil the secondary windings of said transformers.
  3. Protecting system for a zone of direct current electric conductors, comprising circuit breakers on each conductor inside said zone, for each circuit breaker a trip coil, an electric power supply able to feed said coils, a relay controlling said feeding current, current transformers whose cores are constituted of non-magnetic material, all transformers having the same characteristics, the primary winding of each transformer being inserted in one conductor at the point where the said conductor crosses the zone border, and means to connect in parallel with the relay coil the secondary windings of said transformers.
- 40 In testimony whereof I have affixed my signature.

AIMÉ BARTHELEMY FOURNIER.
